UNITED STATES PATENT OFFICE.

JASON W. TOWN, OF SOUTH WOODBURY, VERMONT.

IMPROVEMENT IN LAST-MACHINES.

Specification forming part of Letters Patent No. 39,847, dated September 8, 1863.

To all whom it may concern:

Be it known that I, J. W. TOWN, of South Woodbury, in the county of Washington and State of Vermont, have invented a new and useful Improvement in Machines for Turning Shoe-Lasts, &c.; and I do hereby declare that the following is a full, clear, and exact description of the same, reference being had to the accompanying drawings, making a part of this specification, in which—

Figure 1 represents a side elevation of my invention. Fig. 2 is a front elevation of the same.

Similar letters of reference indicate corresponding parts in the two figures.

The invention relates to an improvement in the guide or model wheel of a graduating last machine, arranging the same in such a manner that without changing the cutters or pattern different sizes of lasts can be produced.

To enable others skilled in the art to make and use my invention, I will proceed to describe it.

Last-machines of the ordinary construction have but one size of guide or model wheel, or a part of wheel, which, of course, corresponds in size with the knives on the cutting-wheel. With this arrangement the proportion cannot be maintained perfectly, and in order to accomplish this object it is indispensable there should be as many sizes of guides as there are different sizes of lasts to be turned by one pattern or model last, each guide varying in size so as to bear the same proportion to the pattern or model last that the cutting-wheel does to the last to be turned.

My invention therefore really consists in using, in a last-machine, different sizes of guides, and in order to have these guides conveniently placed and easy to manage, I have secured them to the periphery of a wheel, A, the middle of each guide a being located equidistant from the center of the arbor b, on which the wheel A rotates. The wheel A rests upon its gudgeons, and it should be located or held in the desired position by a dog or pin inserted in one of the holes c in the side. It is turned by hand, and

that only when a different-sized last is to be turned. The guides are numbered from 4 to 12, and they gradually decrease in size. They are, however, so arranged that the edge of the wheel remains even on one side.

In using my guides I proceed as follows: For instance, if B represents the model-last and C the last to be turned, D being the cutter-head, and if the model is a ten-inch one and right for a ten-inch cutting-wheel, with knives on a circle of one and one-half inch diameter, in order to turn like the pattern, whatever that may be, the guide should be located with the middle section (No. 8) to the pattern. If it is now desired to turn a No. 9 last from a pattern No. 8 man's last, I would locate the section No. 9 of my guide-wheel to the pattern. This section is smaller in all its dimensions than the previous section and to turn a No. 10 a still smaller guide is located toward the pattern; but to turn a last smaller than the pattern a larger guide should be used in the same order in which they are numbered.

My guides are applicable to all graduating last-machines, with but little alteration in the other arrangements.

The variation in the width of the guides effects the length of the lasts, and by having them even on one side of the wheel A the variation in length will all be one way, and it is only necessary that the lever which governs the length of the lasts should be spaced and marked according to circumstances.

What I claim as new, and desire to secure by Letters Patent, is—

1. The employment or use of different sizes of guides in a last-machine, so that with the same pattern and set of knives lasts of different size can be turned and the proportion maintained perfectly.

2. The arrangement of guides a of different size on the periphery of a wheel, A, substantially as and for the purpose set forth.

JASON W. TOWN.
